VALVE LOCK REMOVER AND CATCHER

Robert Monnot, San Carlos, Calif., assignor of
one-half to Charles F. Huling, Mountain View,
Calif.

Application July 19, 1941, Serial No. 403,195

2 Claims. (Cl. 81—3)

The present invention relates particularly to means for removing the split conical locking devices from the lower ends of poppet-valve stems of internal combustion engines, and for catching the same in such a manner as to make their removal from the engine a very simple and easy procedure.

It is one object of the invention to provide a tool of the character indicated that can be readily applied to valve stem assemblies of all types commonly found in internal combustion engines, and accommodate itself to any existing variation in spacing of the locks from the lower end of the valve stems.

It is also an object of the invention to provide a tool of the character indicated provided with self-contained means for breaking the valve lock parts away from the valve stem, and positively receive and retain the parts when they fall away from the stem.

It is also an object to provide a tool of the character indicated that will be economical to manufacture, that will consist of but few and simple parts, and that will be strong, durable, and highly efficient in its practical application.

In the drawing:

Figure 1 is a plan view of a device embodying my invention, with a valve stem shown in section in position thereon.

Figure 2 is a sectional view on line 2—2 of Figure 1.

Figure 3 is a sectional view on line 3—3 of Figure 1 with a portion of a valve stem and associated parts thereon.

Figure 4 is a perspective illustration of the positioning guide mounted on the bottom of the device.

Figure 5 is a perspective illustration of a portion of the forward end of the device on line 3—3, Figure 1.

In the specific embodiment of the invention herein disclosed, I show at 1 an elongated strip of sheet metal having side flanges 2 and 3 formed thereon, the tapering portion of the strip forming a handle 4, and the wider end of the strip forming a basin 5 by reason of the flanges 2 and 3 being carried, or continued, around the end of the same as shown.

In the bottom of basin 5 is a slot 6. This slot 6 is symmetrically disposed along the longitudinal median line of basin 5, beginning at a point adjacent its forward edge as shown, and has a width sufficient to receive the end of a valve stem.

At 7 is shown a flat resilient, or spring mem-

ber, mounted on the bottom of basin 5 rearwardly of the slot 6 and extending forwardly to underlie and close the slot 6 from below and to resiliently support a valve stem when the device is in an operative position.

The spring member 7 is but slightly wider than the slot 6, and mounted on the bottom basin 5 and on each side of the member 7 in parallel relation with the said spring member 7, and consequently with the slot 6, is a vertically depending guide 8, the guides 8—8 forming a guideway 9. The guide parts 8—8 are attached to the bottom of basin 5 as at 10, and are preferably made of resilient material. Being free of attachment throughout their length they readily adapt themselves to any push-rod head they straddle as hereinafter described.

Punched up from the bottom of basin 5, one on each side of the slot 6 and substantially midway the length thereof, and extending laterally with respect thereto and from its two side edges, are upstanding low flanges 11—11.

The device is used in the following manner, the parts now to be referred to being typical of the present methods of construction in the automobile industry.

A portion of an engine block is indicated at 12, with a valve stem guide at 13 and a portion of a valve and stem at 14. The customary split conical lock is shown at 15 on the lower end of the stem 14, the valve-spring retainer being shown at 16, and the spring itself at 17. As shown here the retainer 16 is elevated, and the spring 17 compressed in the usual manner by any suitable tool not shown. The upper end of the push-rod actuating the valve 14 is indicated at 18.

The constant pounding of the push-rod on the valve-stem invariably results in seating the parts 15 so tightly in the spring retainer 16 that when 40 the spring is compressed and the retainer raised into some such position as shown, these parts 15, and the valve upon which they are mounted, are also elevated, forming a gap between the push-rod and the valve-stem. The tool described is thrust into this gap with the guides 8—8 straddling the push-rod head, thus centering the device longitudinally thereon, so that the push-rod will rest directly on the spring 17 when it drops down. A tap on the top of the valve 14 45 will now cause the parts 15 to separate from the retainer 16 and to cause the valve to drop down on to the spring member 7.

In the above described operation the descent of the valve-stem may release one of the parts 15, both of said parts, or neither of them. If

either part 15 falls away from the stem it is, of course caught in the basin 5. If one of the parts 15, or both of them, which is usually the case, remain in position on the valve-stem, it is only necessary for the operator to move the device 5 forwardly and backwardly a few times, or rotate the device a little in opposite directions about the axis of the valve-stem, to cause the parts 11-11 to engage them and force them off of the stem into the basin.

The part 5 is referred to as a "basin," but only in the sense of holding solid articles. The sides need not be closed in such a manner as to hold a fluid substance but only sufficiently to prevent the escape of the lock 15. Likewise, while a certain arrangement of slot 6 and underlying spring 7 is shown, they may be arranged in various ways and, on occasion, may be eliminated in whole or in part. Usually it is necessary to tap the valve a number of times to force the parts 11-11 between the parts 15-15 sufficiently far to pry them off, and the spring 7 provides a resilient support for the valve-stem and permits this operation.

Having now illustrated and described one specific embodiment of my invention, I wish it to be understood that my invention is not to be limited to the specific form or arrangement of parts described and shown except insofar as such limitations are specified in the appended claims.

I claim:

1. A device of the character described comprising, a handled basin adapted to be inserted between a poppet-valve push-rod and its cooperating valve stem, and having a slot formed in the bottom thereof sufficiently wide to permit the passage of a valve stem therethrough, a resilient member mounted on the bottom of the basin to underlie and cover said slot and resiliently support a valve stem thereon, guide means disposed on the underside of the basin on either side of the resilient member to form a guideway operative to slidably engage a push-rod head and center the resilient member thereon, and means disposed on the inner surface of the basin and on either side of said slot, operative to engage the split-cone lock members on the overlying valve stem to dislodge the same therefrom.
2. A device of the character described comprising, a handled basin adapted to be inserted between a poppet valve push-rod and its cooperating valve-stem and having a passage formed in the bottom thereof of sufficient size to permit the passage of a valve-stem therethrough, resilient means associated with said basin and disposed to lie across and resiliently obstruct said passage and support a valve-stem, and split cone lock member dislodging means disposed on the inner side of the basin adjacent said passage.

ROBERT MONNOT.
